UNITED STATES PATENT OFFICE.

ALVIN JUDD AUSTIN, OF SHELBY, NEBRASKA.

EGG-BEATER.

SPECIFICATION forming part of Letters Patent No. 428,999, dated May 27, 1890.

Application filed March 3, 1890. Serial No. 342,412. (No model.)

To all whom it may concern:

Be it known that I, ALVIN JUDD AUSTIN, of 5
Shelby, in the county of Polk and State of
Nebraska, have invented certain new and use-
ful Improvements in Egg-Beaters; and I do
hereby declare the following to be a full, clear,
and exact description of the invention, such
as will enable others skilled in the art to
which it pertains to make and use it, refer-
10 ence being had to the accompanying drawing,
which forms part of this specification.

My invention relates to an improvement in
egg-beaters; and it consists in the particu-
lar construction hereinafter described and
15 claimed.

The object of my invention is to construct
an egg-beater in which the handle or sup-
port, the operating-rod, and the partially-re-
volving rod are constructed entirely of wire,
20 whereby a very cheap, simple, and durable
egg-beater is produced.

The accompanying drawing represents a
side elevation of an egg-beater which embodies
25 my invention, parts being shown in one
position in solid lines and in another pos-
ition in dotted lines.

A represents the handle or frame, which is
preferably given the shape here shown, and
which has an eye B formed upon each of its
30 ends, so as to act as a guide and support to the
two operating parts. Passed down through
the upper eye is the operating-rod C, which
is provided with a bend or projection D at
any suitable distance above its lower end.
35 The upper end of this rod may be formed into
a handle F, of any desired shape that may be
preferred, and by means of which the rod is
given a simple reciprocating movement
through the upper eye of the handle or frame
40 A. Between the two ends of the frame A is

placed a spiral wire G, with its lower end
passing through the lower eye B, and to this
lower end is attached a vibrating egg-beater
H, of any suitable construction. All that por-
tion of the wire G between the two coils or 45
bends J, which act as stops to prevent the
wire from having an endwise movement, is
formed into an even spiral, so that as the op-
erating-rod C is reciprocated its bend or pro-
jection D, by bearing against the inclined sur- 50
face of the spiral wire G, causes this wire to
revolve first in one direction and then in the
other. As will be seen, this spiral wire is
coiled upon the lower portion of the operat-
ing-rod, and thus the operating-rod is made 55
not only to support the spiral wire in a verti-
cal position, but also to cause it to revolve.

Having thus described my invention, I
claim—

In an egg-beater, the combination of the 60
frame having an eye at its upper and lower
ends, the spiral wire placed between the ends
of the frame, and which has its lower end
passed through the lower eye of the frame
and provided with a stop that engages the top 65
of the said eye, and the upper end of the said
spiral wire formed into an eye, and an oper-
ating-rod which passes through the upper eye
of the frame and the eye at the upper end of
the spiral wire, and provided with a lateral 70
projection at or near its lower end, which
engages the said spiral wire, and the beater
secured to the lower end of the spiral wire,
substantially as shown and described.

In testimony whereof I affix my signature in 75
presence of two witnesses.

ALVIN JUDD AUSTIN.
